UNITED STATES PATENT OFFICE

2,185,823

CIRCUIT BREAKER

Ludwig S. Walle, Lansdowne, Pa., assignor to
General Electric Company, a corporation of
New York

Application January 28, 1938, Serial No. 188,275

7 Claims. (Cl. 200—116)

My invention relates to circuit breakers, more particularly to circuit breakers of the type known as branch-circuit circuit breakers which provide the protective features characteristic of a fuse as well as the additional advantages of a manually operated switch, and has for an object the provision of a simple, reliable and inexpensive circuit breaker of this character.

Heretofore, branch circuit breakers have been provided with a thermal release arranged to trip the circuit breaker upon the occurrence of an overload, and with a manually operable handle for opening and closing the circuit independently of the thermal release. However, much is yet to be desired in such circuit breakers hitherto proposed to replace fuses because of the fact that the arc has been extinguished by means of magnetic blowouts and the like with resulting flame and arc gases. Inasmuch as branch circuit breakers as applied to panel-boards for the protection of lighting circuits, are called upon to interrupt currents of very considerable magnitude, as high as 5,000 amperes or more, when the breaker carries out the short circuit protective functions of a fuse, it will be apparent that a considerable quantity of arc gases are generated and that the flame of the arc is quite appreciable; these two features being undesirable for circuit breakers for household use. Furthermore, since the fuses which have hitherto been used accomplish this interruption of the circuit without spurts of flame, and without loud popping accompanying the interruption of an overload current of high magnitude, a satisfactory circuit breaker should also possess these advantages.

In carrying out my invention in one form thereof, I provide a circuit breaker which is capable of interrupting overload currents of large magnitude at lighting circuit voltages without the emission of flame or arc gases, and without noise, by enclosing the contacts in a sealed steel chamber of restricted volume. More specifically, I provide a mechanism for opening and closing the contacts with a snap action in response to movement of an operating handle and for opening with a snap action the contacts in response to overload current. The contacts move within the sealed metallic chamber so that when an arc is drawn between the separating contacts the gas pressure within the chamber increases quite rapidly. This pressure may be of the order of 1000 pounds per square inch. The resistance of the arc increases rapidly with pressure so that as the pressure is built up the resistance becomes so great that the arc can no longer exist, and it is extinguished.

For a more complete understanding of my invention, reference should now be had to the accompanying drawing wherein I have shown diagrammatically in Fig. 1 a side view partly in

section of a circuit breaker embodying my invention; Fig. 2 shows the parts of the circuit breaker of Fig. 1 just before the contacts are closed, while Figs. 3 and 4, illustrate an improved form of a circuit breaker embodying my invention.

Referring now to Fig. 1, I have shown my invention in one form as applied to a branch circuit breaker suitable for lighting circuits indicated by the conductors 10 and 11. The circuit breaker, mounted on an insulating base 12, comprises a frame 13 for the operating mechanism, a bi-metallic thermal element 14 and an arc interrupter 15. The frame 13 has an upturned end 16 from which is pivotally supported at 17 an operating member 18 provided with an operating handle 19. The operating member 18 has an extension 20 to which is rigidly secured a rivet or projection 21 arranged to cooperate with notches 22 provided in a pair of parallel L-shaped links 26 between which the member 18 moves. One pair of adjacent ends 29 of the parallel links 26 are pivotally secured at 30 to the movable contact member 31 of the arc interrupter 15. The other ends 33 of the links 26 are provided with projections 34 which are engaged by adjacent ends of a pair of springs 37 which embrace the links 26. The other ends of the springs are secured to inwardly projecting ends 38 of the frame 13. It will be observed that the circuit represented by the conductors 10 and 11 may be traced from conductors 11 through the branch circuit breaker by conductor 40, thermal element 14, flexible conductor 42, movable contact member 31, stationary contact member 43 provided in the arc interrupter or compression chamber 15 and by conductor 44 to the conductor 10. The contact members 31 and 43 are constructed of an arc resistant material, for example silver molybdenum, but other arc resistant materials may of course be used.

The operating mechanism of the branch circuit breaker is trip free; that is to say, the operating handle 19, even though operated, cannot maintain a closed circuit if a current exists of sufficient magnitude to open the breaker. For example, in the operation of my invention it will be observed that the circuit breaker is normally closed after it has opened in response to a predetermined maximum current, the parts then being in the relative positions shown in Fig. 1, by moving the operating handle 19 downwardly, whereby the operating member 18 is rotated in a clockwise direction around its pivot 17 to bring its projection 21 into engagement with the notch 22 in the links 26 and thus move the links 26 a slight amount in a clockwise direction and also bodily toward the left. When the handle 19 strikes the end of the frame 38 the movable parts are in the positions shown in Fig. 2. A projection 48 extending from the links 26 is moved from

the position shown in Fig. 1 toward the left past a latch 49 carried by the thermal element 14. The latch may of course be operated by means other than a thermal element. At this time the movable contact 31 has not engaged the stationary contact 43 to close the contact. As soon, however, as the operating handle 19 is released the springs 37 rotate the links 26 about the projection 48 to operate the movable contact 31 into engagement with the contact 43 with a snap action, thus closing a circuit through the breaker. The springs 37 expend only a part of their energy in operating the contact 31 to the closed position. The remaining energy is at all times available for operating with a snap action the contact 31 to the open circuit position in response to overload or short circuit current. The floating links 26 in the final or closed circuit position are free of the operating handle. The links 26 as they free themselves from the handle 19 impart to the handle through the projection 21 an impulse which returns the handle towards the off position. As shown in Fig. 1, the handle is retained in an intermediate position by the engagement of the end 20 of the handle with the leaf spring carried on the frame. By moving the handle 19 from this intermediate position in a counterclockwise direction, as viewed in Figs. 1 and 2, a projection 18a carried by the operating member 18 operatively engages the thermal element 14 to move it to release the latching projection 48. The springs 37 thereupon operate the movable contact 31 with a snap action to the open circuit position. It will be understood that the movable contact 31 may also be moved to the open position by moving the handle 19 downward whereby the pin 21 moves the floating member 26 about the projection 48 as a pivot to the open position shown in Fig. 2.

Assuming now that an overload occurs on the circuit represented by the conductors 10 and 11, the thermal element 14 is flexed in a clockwise direction to release the latching member 49 from the latching projection 48. The springs 37 thereupon cause the movable contact 31 to move toward the right as viewed in Fig. 1 with a snap action to the open circuit position shown in Fig. 1. As the movable contact 31 leaves the stationary contact 43, an arc is drawn between them. The arc interrupter 15 comprises a steel cylinder 50 within which a pair of kerosene-free fiber bushings 51 and 52 extend. I have found that kerosene-free fiber or an equivalent material is essential to the operation of my invention and deem its use in the arc chamber an important part of my invention. The steel or metallic cylinder and the insulating members are so arranged as to provide a sealed chamber of relatively small volume, such that the arc causes a rapid increase in air pressure in the chamber, the high air pressure exerting an opening force on the movable contact. This increase in pressure is due to the heating by the high temperature of the arc of the air within the chamber. The rise in pressure may be further accentuated by the heating of other gaseous fluids produced by the action of the arc on the air and the materials within the cylinder.

In order to produce a strong and rigid construction of the arc chamber, the bushings 51 and 52 are inserted into the ends of the steel cylinder. The ends of the cylinder are then swaged over the relatively narrow peripheral extensions provided on the bushings. The steel cylinder 50 is in turn enclosed in a casing 60

of insulating material. The stationary contact member 43 has screw threads 61 provided at one end arranged to cooperate with a threaded member 62 forming a part of the conductor 44. The insulating bushing 51 permits a reciprocal longitudinal movement of the movable contact member 31, one end of which is always located in the chamber and the other end of which is always located outside of the chamber.

A leather sealing washer 65 is provided around the movable contact member 31, the washer being provided with an inwardly projecting cylindrical extension 66. Since a certain amount of metal vapor is produced when the circuit breaker interrupts a current of large magnitude, it is necessary to prevent this metal vapor from collecting on the movable contact member 31 where it may harden and interfere with successive operations of the circuit breaker. The leather washer with its inwardly extending projection tends to prevent this collection of the metallic vapor because of its wiping action on the movable contact member 31 and furthermore assists in maintaining a substantially air-tight connection around the movable contact member 31 by its cooperation with the contact member and the walls of the chamber. At the same time the leather washer provides for snap movement of the movable contact by the spring means by offering only relatively slight friction to such movement.

As I have stated, when an arc is drawn between the contacts 31 and 43, the air pressure within the chamber of the arc interrupter increases rapidly. The potential drop across the arc is not entirely dependent on the rise in pressure inasmuch as the cross sectional area of an arc is approximately proportional to the current. It is believed that the arc potential drop is approximately proportional to the inverse square root of the current. This characteristic of the arc, in addition to the rise in pressure in the chamber, causes a quick interruption of the circuit. Furthermore, since the rise in pressure depends upon the magnitude of the current interrupted, it will be seen that the greater the overload current the more quickly will the pressure rise to a point where the arc resistance becomes so great that the arc can no longer exist. Obviously, the pressure within the chamber also exerts an opening force on the movable contact accelerating its speed of opening in proportion to the degree of pressure built up by the heat of the arc.

Of course, it will be understood that in order to reclose the circuit breaker it is only necessary to repeat the operations described in connection with Figs. 1 and 2.

In the modified form of my invention, shown in Figs. 3 and 4, I have provided a rotatable bridging contact 67 which is connected through springs 67a and 67b to a shaft 68 having bearings in each end of a cylindrical enclosure 69 forming an arc chamber. As in the form disclosed in Figs. 1 and 2, arc extinguishing gas pressures may be generated in this chamber. The bridging member 67 has contacts 70 and 71 at its ends which cooperate with fixed contacts 72 and 73. In the form shown, three bridging members 67 are connected to the shaft (only one being shown) forming a three-pole circuit breaker. The shaft 68 is connected for rotary movement through a predetermined angle such as 90° by means of a pair of links 74 and 75 at each end to an operating shaft 76 parallel therewith and outside of

the chamber formed by the enclosure 69. This shaft 76 is connected by means of a link 77 having one end rigidly secured to the shaft 76 and a link 78 pivoted on the other end of the link 77 to the left-hand end of a floating operating member 79, a pivotal connection being provided between the link 78 and the operating member 79. This floating member 79 may conveniently be formed as two members or plates secured together in parallel relation and spaced sufficiently far apart to receive between them the link 78 and also, at their other ends, a roller 80 which rides on an upright guide member 81. The right-hand end of the floating member 79 is biased to its lowermost position shown in Fig. 3 by a pair of springs 82, only one of which is shown, one on each side. Also rigidly secured to the floating member 79 is a latching hook 83 which is adapted to engage a roller 84 on the lower end of a trip arm 85 pivoted at the point 86 and biased by the weight of its right-hand portion in a clockwise direction.

As shown in Fig. 3 the circuit breaker is in its open circuit position with the operating handle 87 in its right-hand position. In this position a pin 88 carried by the member 89 to which the handle is secured, engages an inclined face 90 on the lower end of the floating member 79. The member 89 is pivoted on the shaft 76, and, as shown, is in two parallel spaced parts. When the handle 87 is moved toward the left, the pin 88 engages the inclined surface 90 and moves the floating member 79 upward against the force applied thereto by the springs 82, the inclination of the surface 90 at an acute angle with the guide 81 being such that a wedging action and component of forces is produced such that the floating member 79 is raised at its right-hand end against the force applied by the spring, although the left-hand end may be lifted to a certain extent but not enough to move the bridging contact 67 to its closed circuit position. During this movement the roller 80 bears against its guide 81 and rides up the guide.

When the handle 87 reaches its left-hand position, the latching hook 83 has moved up past the roller 84, the lever 85 moving about its pivot in a counterclockwise direction to permit this and the roller 84 has been moved by the overbalanced weight of the lever 85 under the hook 83 to hold the hook. The handle 87 may now be released and the springs 82 will thereupon move the floating member 79 in a clockwise direction about the roller 84 as a pivot thereby still further raising the left-hand end of the member and moving the bridging contact into engagement with the stationary contacts.

In this position of the floating member the pin 88 is opposite a notch or recess 91 in the lower side of the floating member 79. With the switch thus closed if the handle 87 should be moved back toward the left the pin 88 moves into the recess 91 having no effect on the floating member. This recess is furthermore deep enough to permit the floating member 79 to move downward sufficiently to move the switch arm to its open circuit position without engaging the pin 88. Therefore, this recess 91 makes it impossible to hold the circuit breaker in its closed position by means of the handle and the circuit breaker is therefore trip free of the handle.

Cooperating with the arm 85 is current responsive tripping means for opening the circuit breaker in response to a predetermined current therethrough. This means comprises three U

shaped bimetallic thermostats 92, 92a and 92b included in the respective circuits of the circuit breaker so as to be heated by the current. On the upper end of each is a button or knob 93 (only one of which is shown) made of suitable insulating material adjustable to vary the current setting. These knobs are adapted to engage a cross bar 93a, the upper end of a lever 94 pivoted at a point 95 and having its lower end connected to a link 96 connected to the upper end of another pivoted link 97. The upper end of the link 97 is connected through a tension spring 98 to the upper end of a strip member 99 pivoted on a pin 100 and having a projection 101 just beneath the end of the trip lever 85.

As shown, the spring 98 is just to the left of the pivot 100; therefore the member 99 is biased to the position shown in a counterclockwise direction, suitable stops (not shown) being provided to limit its movement. Upon the occurrence of a predetermined overload the upper end of one or more of the thermostats moves toward the left so that the button 93 moves the arm 94 and thereby the upper end of the link 97 toward the right whereby the spring 98 is carried to the right-hand side of the pivot 100. This sets up a component in a clockwise direction whereby the member 99 is turned in that direction with a snap action and the projection 101 caused to move the arm 85 upward and thereby move the roller 84 to the right out of engagement with the hook 83. The floating member 79 is thereupon moved by the springs 82 in a counterclockwise direction about the roller 80 which rests in the inclined guide 105 to the position shown in Fig. 3 thereby opening the circuit breaker. 35

Moreover, the pivot pin 102 of the roller 84 is extended into the path of the member 89 so that the member 89 in the position shown in Fig. 3 engages the pin. Therefore, a slight movement of the handle to the right to its extreme right-hand position pushes the roller 84 out from under the hook 83, thus permitting the circuit breaker to open with a snap action.

Also the member 89 is provided with an extension pin 103 in one side which when the handle is thrown to its extreme right-hand position engages the lower end of the trip member 99 moving it in a counterclockwise direction to the position shown in Fig. 3, thus resetting it in the event that the breaker has been tripped on overload.

To reclose the breaker after opening on overload the handle is moved to the right to reset the trip member 99 and move the pin 88 downward out of the notch 91, the pin engaging the inclined surface 104 and thereby moving the floating member slightly counterclockwise and bodily to the left, the roller 80 riding upward in the inclined guide 105 secured to the guide 81. When the pin 88 passes downward out of the notch the floating member moves to the right in accordance with the bias of the springs 82, the roller 80 moving back down the guide 105.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States is:

1. A circuit breaker comprising a floating actuating member, a movable contact connected

to one end of said actuating member, a spring for biasing the other end of said member for movement in a predetermined direction, a guide for said other end extending in said predetermined direction, an intermediate portion of said member being provided with an operating surface extending at an acute angle with said guide, current responsive latching means for pivotally securing said actuating member at an intermediate point, an operating member provided with a projection engaging said operating surface to thereby move said actuating member bodily against the tension of said spring to a position to be secured by said latching means, whereby upon release of said operating means said actuating member is moved by said spring to actuate said contact to a closed circuit position.

2. A circuit breaker comprising a floating actuating member, a movable contact connected to one end of said actuating member, a roller on the other end of said member, a spring for biasing said other end of said member for movement in a predetermined direction, a guide for said roller extending in said predetermined direction, an intermediate portion of said member being provided with an operating surface extending at an acute angle with said guide, current responsive latching means for pivotally securing an intermediate portion of said actuating member, a pivoted operating member provided with a projection engaging said surface upon pivotal movement of said operating member in a predetermined direction to thereby move said actuating member bodily against the tension of said spring to a position to be secured by said latching means, whereby upon release of said operating means said actuating member is moved by said spring to actuate said contact to a closed circuit position and to disengage said inclined portion from said projection, and means operated by said operating member for releasing said latching means.

3. In a circuit interrupter, a pair of contacts one of which is movable, an actuating member for moving said movable contact between open and closed circuit positions, means releasably retaining one point of said actuating member in a fixed position serving as a pivot point about which said actuating member is rotatable to a closed circuit position, a spring applying a biasing force to move said actuating member to said closed circuit position and at the same time biasing said point on said actuating member to move upon release of said retaining means and move the movable contact toward open circuit position, a guide for said actuating member, said actuating member being provided with an operating surface extending at an acute angle with said guide, and an operating member cooperating with said operating surface.

4. In a circuit interrupter, a pair of contacts one of which is movable, an actuating member for moving said movable contact between open and closed circuit positions, holding means releasably retaining one point of said actuating member in a fixed position serving as a pivot point about which said actuating member is rotatable to a closed circuit position, a spring applying a biasing force to move said actuating member to said closed circuit position and at the same time biasing said point on said actuating member to move upon release of said retaining

means and move the movable contact toward open circuit position, a guide for said actuating member spaced from the line of action of the force applied by said spring, said actuating member being provided with an operating surface on the opposite side of said line of action from said guide and extending at an acute angle with said guide, and an operating member cooperating with said operating surface to move said actuating member against the tension of said spring to a position to be secured by said holding means, and means operated by said operating member for actuating said holding means to release said actuating member.

5. In a circuit interrupter, a pair of contacts one of which is movable, an actuating member for moving said movable contact between open and closed circuit positions, means releasably retaining one point of said actuating member in a fixed position serving as a pivot point about which said actuating member is rotatable to a closed circuit position, a spring applying a biasing force to move said actuating member to said closed circuit position and at the same time biasing said point on said actuating member to move upon release of said retaining means and move the movable contact toward open circuit position, a guide for said actuating member spaced from the line of action of the force applied by said spring, said actuating member being provided with an operating surface extending at an acute angle with said guide, and an operating member cooperating with said operating surface, said actuating member being provided with a recess adjacent said operating surface for receiving said operating member when said actuating member is in a closed circuit position.

6. A circuit breaker comprising an actuating member, a movable contact connected to one end of said actuating member, a spring for biasing the other end of said member for movement in a predetermined direction, a guide for said other end, said member being provided with an intermediate operating surface extending at an acute angle with said guide, current responsive latching means for pivotally securing said actuating member at an intermediate point, and an operating member engaging said operating surface to move said actuating member against the tension of said spring to a position to be secured by said latching means.

7. A circuit breaker comprising a floating actuating member, a movable contact connected to one end of said actuating member, a spring for biasing the other end of said member for movement in a predetermined direction to a closed circuit position, a guide for said other end extending in said predetermined direction, said member being provided with an operating surface intermediate its ends extending at an acute angle with said guide, current responsive latching means for pivotally securing said actuating member at an intermediate point, an operating member provided with a projection engaging said operating surface to thereby move said actuating member against the tension of said spring to a position to be secured by said latching means, said actuating member being provided with a recess adjacent said operating surface for receiving said projection when said actuating member is in a closed circuit position.

LUDWIG S. WALLE.
